UNITED STATES PATENT OFFICE.

PERCY HUGHES HEWITT, EDWIN A. COCKLE, AND CHARLES MATTHEWS,
OF LONDON, ENGLAND.

SEWING-MACHINE SHUTTLE.

SPECIFICATION forming part of Letters Patent No. 639,044, dated December 12, 1899.

Application filed March 29, 1898. Serial No. 675,559. (No model.)

To all whom it may concern:

Be it known that we, PERCY HUGHES HEWITT, barrister at law, of Oakley House, Spring Grove, Isleworth, London, W., and EDWIN 5 ALLEN COCKLE and CHARLES MATTHEWS, bootmakers, of 34 Victor Terrace, Harrow road, Willesden, London, N. W., England, have invented a new and useful Sewing-Machine Shuttle, (for which an application for 10 patent has been filed in Great Britain, dated the 1st day of October, 1897, No. 22,488,) of which the following is a full, clear, and exact description.

This invention relates to shuttle sewing- 15 machines; and it consists, essentially, in an improved construction of shuttle whereby it is adapted to contain an ordinary commercial bobbin or reel of thread, so as to avoid certain well-known disadvantages incidental 20 to the use of a special spool of small capacity, such as is generally employed, these disadvantages including not only greater complication and consequent enhanced cost of the machine due to the necessity of providing 25 special mechanism for winding the spools, but also loss of time due to the necessity of frequently stopping, removing, and accurately replacing the work and of winding thread from the ordinary reel onto the special 30 spool, such loss bearing a high ratio to the total time worked.

The invention will be described with reference to the accompanying drawings, forming part of this specification, wherein—

35 Figure 1 is a rear end view of a shuttle constructed according to this invention, and Fig. 2 is a longitudinal view, partly in section, of the side of the shuttle which lies next to the shuttle-race and needle-groove. Fig. 3 is a cross-section on line 3 3, Fig. 4, the internal fittings being removed; and Fig. 4 is a horizontal section. Fig. 5 is a cross-section on line 5 5, Fig. 6; and Fig. 6 is a top plan view of the shuttle, showing the thread-guide and 40 tension device. Figs. 1 to 6 are drawn to an enlarged scale.

The shuttle A, as shown in Figs. 1 to 6, may conveniently be formed of a metal casting, and is of the same general configuration 45 as other sewing-machine shuttles, except that instead of being of D form in cross-section

and open at the flat side it is of nearly circular cross-section, the flattened side a (which works, as usual, against the shuttle-race, so as to pass to and fro across the needle-groove) 55 being closed and made of a width only sufficient to retain the shuttle in proper working position in the shuttle driver or cradle. The flattened side of the shuttle being closed (whereby risk of any loose thread accidentally escaping from within the shuttle, as well as liability of the needle-point catching 60 in the shuttle, is obviated) and being of less breadth than the diameter of the contained reel the latter cannot be introduced into the 65 shuttle in the ordinary way, and provision is made for introducing the reel in the longitudinal direction at the heel end by making the heel of the shuttle a detachable cap B in the form of a circular cup fitting snugly by 70 its flange b into a correspondingly circular seat in the rear end of the body part A of the shuttle, so that the needle-thread loop in slipping over the body of the shuttle will encounter no obstacle and not be liable to catch 75 on the detachable heel-cap.

The heel-cap is securely locked in position preferably by inwardly-projecting studs c, fixed in the body part A of the shuttle, engaging (by a partial longitudinal and rotary 80 movement of the heel-cap) in bayonet-slots c', cut in the flange b, these slots being of such shape that the outward pressure of the reel on the heel-cap due to the thrust of the internal spring, hereinafter described, will tend 85 to retain the studs in engagement in the slots, so as to prevent any tendency of the heel-cap to become unfastened by the constant jarring produced by the action of the shuttle-driver at each reversal of the direction of motion. 90 With this object the circular portions of the slots c' make respectively less than a right angle with the entering portions of the slots which are in the longitudinal central plane of the cap, so that the outward thrust on the 95 heel-cap will tend to retain the cap in the position shown—that is to say, with the studs c at the extreme closed ends of the bayonet-slots c'—while any looseness or shake between the heel-cap and body portion will be prevented. 100

The heel-cap B is provided with holes d for

turning it in its seat by means of the finger or a suitable tool and with an inwardly-projecting central cone e , adapted to enter the bored center of the reel R . The reel R is held between the said cone e and a similar cone f at the other end formed upon a disk f' , fitted to slide upon a dead-spindle g , fixed in the body of the shuttle, the disk being prevented from turning with the reel by the angular section of the spindle, as seen in Fig. 5, and means (such as a head upon the spindle or a small cross-pin g') being provided for retaining the disk and spring upon the spindle g when the reel is removed. Between the disk f' and a suitable abutment formed by the boss g^2 , in which the spindle is fixed, a spiral spring h is confined, so as by its pressure against the disk f' to retain the reel securely in position to rotate upon and between the cones e f as centers, with sufficient friction to check the rotation of the reel so far as may be necessary to prevent more than the requisite length of thread becoming unwound, said friction also serving to impart tension to the thread, while the range of elasticity of the spring and the length of the guide-spindle g are such as to adapt the shuttle to receive reels of various lengths less than that of the full-sized reel shown. The disk f' works through an aperture (in which it loosely fits) formed in a transverse diaphragm a' in the body of the shuttle, whereby any loose thread which may accidentally become unwound from the reel is prevented from entangling itself with the spring h , the disk f' having a peripheral flange f^2 of such width that the aperture in the diaphragm a' will remain closed even should the disk project beyond the diaphragm, as would be the case when a short reel is used.

The body A of the shuttle has a slit i leading from the open heel end to a hole j at the upper side of the shuttle, partly covered by a spring tension-plate k , fixed to the exterior of the shuttle by an adjustable screw k' , which also serves as the means of regulating the tension given to the thread. A stud k^2 upon the under side of the plate k and entering a hole in the shuttle forms a guide-stop for the thread during the forward movement of the shuttle, while a similar guide-stop during the backward movement is formed by the forward end of the plate k being curved inward and outward, as shown at l in Fig. 2, and housed in an aperture l' in the body of the shuttle. The form thus given to the forward end of the tension-plate k , while offering no obstruction to the passage of the shuttle through the needle-thread loop, admits of the thread being easily passed beneath that end of the tension-plate during the operation of threading the shuttle, as hereinafter described.

In order to prevent any possibility of the shuttle-thread becoming caught under the rear end of the tension-plate k , the rear portion of the plate is curved somewhat toward the flat side of the shuttle, as shown in Fig.

6, and its extremity l^2 is bent downward, so as to lie snugly against the body of the shuttle, as shown in Fig. 2.

m is a thread-guide, of wire, fixed within the body of the shuttle by its angular bent end m' being brazed or riveted in a hole in the side of the shuttle, the other end being free and projecting sufficiently beyond the open heel end of the body part A to admit of the thread being readily slipped behind it before the reel is introduced into the shuttle. This guide m is provided with a loop m^2 at about the middle of the length of the reel, through which the loop-thread runs from whichever part in the length of the reel it may be drawn, the straight portion of the wire m lying in the upper of the two corner spaces formed by the meeting of the flat side a with the tangential portions a^2 a^3 , connecting that side with the circular portion of the periphery of the shuttle, as shown in Figs. 1, 3, 5, and 6, while the loop m^2 projects over the reel toward the slit i and hole j , as shown in Figs. 5 and 6.

The operation of threading the shuttle may be very readily performed and is as follows: The reel having been introduced into the body of the shuttle, so that the thread in unwinding will cause the reel to rotate toward the left hand, (looking from heel to point of the shuttle,) the end portion of the thread which has been retained in the hand is slipped behind the guide-wire m from beneath, then through the slit i up to the hole j , then brought around, so as pass under the forward end l of the tension-plate k , and finally emerge from under said plate at the side opposite to that at which the hole j is situate. The thread M will now have assumed a position substantially as indicated in Figs. 5 and 6, and the heel-cap B having been inserted and locked, as already described, the shuttle is ready to be placed in the machine.

It will be observed that in the operation of threading the shuttle, as above described, there is no possibility of delay being caused through the difficulty of thrusting the end of the thread through a hole or holes.

It will be obvious that the heel-cap B may be secured to the body portion A of the shuttle by other means than those hereinbefore described without departing from the spirit of the invention. Thus, for example, the heel-cap might be arranged to screw into the body of the shuttle, or be held in position by a spring catch or catches, or be attached to the body of the shuttle by means of a hinge at the flat side of the latter and a latch at the opposite side, the essential characteristic of all the arrangements remaining the same—namely, that provision is made for introducing the reel into the shuttle in the longitudinal direction at the heel end and for retaining the reel in position substantially as already described.

We claim—

1. A sewing-machine shuttle open at the

heel end, a removable cap fitting said open end, the cap and shuttle being provided one with a pin and the other with a locking-slot, the inner end of the slot trending backward 5 or toward the edge of the member containing it, whereby the cap must be moved inward to release it, a spring and means for transmitting the trend of the spring to the cap through the spool.

10 2. A sewing-machine shuttle open at the heel end for the insertion of a spool, a cap for closing this end the cap having an inwardly-projecting conical spool-center, a cap and shuttle-locking means requiring an inward movement of the cap to free it, a similar outwardly-projecting spool-center within the shuttle and slidable longitudinally thereon and a spring acting upon the inner center to press it outwardly whereby when the spool is 20 inserted the cap is held securely against removal, substantially as described.

15 3. A sewing-machine shuttle open at the heel end for the insertion of a spool, a cap for closing this end having an inwardly-projecting conical spool-center, a cap and shuttle-locking means requiring an inward movement of the cap to free it, a center for the opposite end of the spool having an outwardly-projecting centering-cone and slidable lengthwise 30 the shuttle, the shuttle having bearing-supports surrounding this center, a stop limiting the outward movement of the center, and a spring behind the center acting to press it outwardly whereby when the spool is between 35 the centers the cap is held securely against removal, substantially as described.

4. A sewing-machine shuttle open at the heel end for the insertion of a spool, a cap for closing this end having an inwardly-projecting conical spool-center, means for locking 40 the cap in place held against disengagement by outward pressure upon the cap, a complementary center within the shuttle mounted to slide longitudinally thereon and having an axial non-circular hole, a pin slidably fitting 45 within said hole and secured at its inner end to the shuttle and provided with a stop outside the center, and a spring behind said center pressing it outwardly, whereby the cap is held securely when the spool is in place, substantially as described.

5. A shuttle, having an open end, and a cap fitting the same having a spool-center thereon, a spring-held inner center, a spool between centers, and means for locking the cap and 55 shuttle together held against disengagement by the pressure of said spring acting through the spool.

6. A shuttle having an end facing opening at the heel for the insertion of the spool, a cap 60 fitting said heel-end opening, and a spring-bar secured by its inner end within the shuttle and having its free end extending to the heel, said spring-bar having a thread guide or eye formed therein, substantially as described. 65
